UNITED STATES PATENT OFFICE

ROY D. MAILEY, OF EAST ORANGE, NEW JERSEY, ASSIGNOR TO GENERAL ELECTRIC VAPOR LAMP COMPANY, OF HOBOKEN, NEW JERSEY, A CORPORATION OF NEW JERSEY

GAS OR VAPOR DISCHARGE DEVICE

Application filed October 25, 1928. Serial No. 314,929.

The present invention relates to gas or vapor electric discharge devices and methods of operating the same. The invention relates more particularly to gas or vapor electric discharge lamps having a gas or vapor filling of component parts which cooperate to give the lamp uniformity during the life of the lamp both in operating characteristics and in the color of the light emitted from the lamp.

The main object of the present invention is the production of an electric gaseous discharge lamp operable on the usual commercial circuits of 110 or 220 volts. For use on direct current a lamp embodying my invention is provided with an anode and a hot cathode such as a filament of pure tungsten or thoriated tungsten, or of the type wherein an oxide coated nickel electrode body is heated by such a filament. In an embodiment of my invention for use on alternating current I use two anodes and a similar hot cathode, connected across an alternating current source in a similar manner to the well known Cooper Hewitt alternating current rectifying lamp. In both said embodiments, the gas filling comprises a mixture of gases having low average atomic weight, for example, helium 85-95% and neon 15-5% substantially, wherein one of said gases, the major component, supports electric conduction, and the other emits its characteristic radiation by excitation by collision, whereby the lamp has the desired radiation characteristic, in this case that of neon. Because of the low average atomic weight of the gas filling deleterious disintegration of the electrodes and other parts of such lamps which are bombarded by positive carriers is reduced and maintained at a minimum.

Various other objects and advantages of the invention will be obvious from the following particular description of forms of discharge devices embodying the invention or from an inspection of the accompanying drawing, and the invention also consists in certain new and novel features of construction and combinations of parts hereinafter set forth and claimed.

In the accompanying drawing Figs. 1 to 6

somewhat diagrammatically show for purposes of illustration in vertical elevation forms of devices embodying the invention, together with diagrams of electric circuits therefor.

According to the invention and as shown in the drawing there is used in connection with the cathodes a material for producing electrons in space which material is adapted to emit electrons prolifically when under the influence of a hot body. In the forms of apparatus used to illustrate the invention, an electric resistor heater is used in association with a body of material such as an oxide, hydroxide or carbonate of metal such as calcium, magnesium, barium, strontium, lithium, thorium, or the like, which material is coated over the resistor or is otherwise mounted in operative relation thereto. The gases or vapors used for sustaining a discharge are the rare gases such as neon, helium, argon, etc., mercury, the vapors of sodium, lithium, potassium, calcium and the like or mixtures thereof. In a gaseous discharge device for example, when current is passing therethrough, movement of electrons and atoms and molecules therein results in bombardment of the several parts of the device by the ions and electrons which are in the gas or vapor space. The ions of certain gases are of such mass that the bombardment of solid parts of the device thereby results in the breaking down of those parts and in deleterious effects on the device. Such deleterious bombardment is evidenced by blackening of the transparent walls of the device envelope, caused by sputtering of the electrodes through positive carrier bombardment and the depositing of the sputtered off parts onto the envelope wall. The envelope walls themselves are also bombarded and particles thereof sputtered and in such cases decomposition of the material of the wall takes place with the resultant freeing of deleterious gases into the envelope space. The results of such effects are reduction of the efficiency of the operation of the device or the complete incapacitating thereof through change of operating characteristics, or through the prevention of passage of de-

sirable radiations through the device envelope by such a blackening or darkening by sputtered material.

Some vapors and gases however, have ions whose mass or weight is considerably less than that of others and these are most desirable for carrying current through the device. It is not always the case, however, that gases which have comparatively low weight or mass have desirable radiation characteristics. I have found that certain gases or vapors of comparatively high weight or mass have desirable characteristics of radiation and further that the radiations from such gases or vapors will predominate over those of certain other gases or vapors even when they are present with other gases or vapors in only very small amounts. I have further discovered that there are certain combinations of gases such, for example, as a combination or mixture of two gases in which one having ions of comparatively large mass or weight can be used in very small proportions with the other having ions of comparatively low mass or weight in correspondingly great proportions. I have further discovered that gases or vapors can be chosen in the above said relation with the further relation that the gas having the greater mass or weight of ions requires the expenditure of a lower amount of energy for the production of radiations therefrom than does the other gas and that the said other gas can be used to transmit energy to said heavier weight gas for the production of radiations therefrom. The preponderance of the lighter weight gas and the number of its ions over those of the heavier weight gas contributes to the efficiency in the transmission of radiation producing energy to said heavier gas. A particular example of a combination of gases according to the above statement of the invention is a mixture comprising about 95% helium and about 5% neon. The weight of the helium ion is so low that a discharge device having electron emissive material of the substances above noted will have a comparatively long and useful life. On the other hand the neon, whose ions have comparatively large mass or weight, is present in such a comparatively small amount and the percentage of neon ions present is so small that bombardment of the electron emissive material by ions thereof is so comparatively infrequent that the operative life of the device is not materially affected. Further, when helium and neon are used in a discharge device in the amounts above stated visible light and other radiations from the neon greatly predominate over any radiations which may be produced from the helium. A specific example embodying the purposes and advantages of the invention above noted or otherwise apparent comprises a sealed envelope of glass or quartz having

a solid anode therein, a filling comprising on the order of 90% to 95% helium and 10% to 5% neon and a cathode which consists of an electric resistance heater having positioned in operative relation thereto or more particularly, formed as a coating thereover, a layer or layers of barium oxide. When connected to a suitable source of current, alternating or direct, of a voltage sufficient to produce a discharge therethrough, radiations characteristic of the neon will be produced, the helium will operate as the main current carrying medium and the neon will serve as the main light producing medium. The barium oxide under the influence of the electric heater cathode will serve as a prolific source of electrons which will be accelerated through the potential gradients in the discharge space and will bombard particularly the helium atoms and ionize them and cause the multiplication of current carriers. In a device of this kind having a discharge distance of about 18 inches in a tubular envelope of about 1 inch in diameter and with 300 volts alternating current supply and with vapor pressure of about 3 to 10 mm. of mercury, the device will operate for more than 6000 hours.

In Fig. 1 is illustrated a direct current lamp embodying the invention in which the longitudinal envelope 1 has sealed thereinto at one end the anode 3 which is connected to the lead 5 for connection to the positive side of a source of direct current. At the opposite end of said envelope is mounted the cathode, shown more in detail in Fig. 6, comprising the resistor 6, connection to which is made through the leads 8 and 10 sealed through said envelope 1, and the cylindrical shield 12 of a metal such as nickel, iron, tungsten or other suitable material, mounted about said resistor 6 and having upon its outer surface a coating 13 of an oxide, a hydroxide or a carbonate of a metal such as barium, or other electron emissive material. Connection is made from said electrode 12 through the lead 14 to said resistor 6 by way of said lead 10 at a point outside said envelope 1. Said lead 10 is also connected through the resistance 16 and the inductance 18 to the negative supply main 20. Connection is made from the other side of said resistor 6 through said lead 8, switch 22 and adjustable resistance 24 to said main 5.

In Fig. 2 is illustrated an alternating current rectifying lamp comprising the sealed envelope 30 having sealed thereinto at one end the spaced apart anodes 32 and 33 which are connected respectively through the resistances 35 and 36 to opposite ends of the transformer secondary 38 which is in operative relation to the primary 40. At the end of said envelope 30 opposite from said anodes 32 and 33 is mounted a hot cathode structure the heater 42 of which is connected through

the leads 44 and 45 to spaced apart intermediate points on said secondary 38. Positioned about said cathode heater 42 is an activated sleeve or cathode 46 similar to the corresponding part 12 of Fig. 1. This element 46 is connected through the lead 48 to said conductor 45 at a point outside the envelope.

In the embodiment of the invention illustrated in Fig. 3 the closed envelope 130 of glass, quartz or other suitable material has sealed thereinto at one end the spaced apart anodes 132 and 133 which are connected through the resistances 54 and 55 respectively to opposite ends of a transformer secondary 56 which is in operative relation to the transformer primary 58. At the end of said envelope 130 opposite from said electrodes 132 and 133 is mounted the hollow cylindrical cathode 60 which is of a material such as platinum, nickel, iron, tungsten or other suitable material which has over its outer surfaces a coating of an oxide, hydroxide, or carbonate of a metal such as calcium or barium and which is connected by conductor 62 through the inductance 64 to a midpoint on said secondary 56. About said electrode 60 is positioned the cylindrical shield 66 which is of iron, nickel, tungsten or other suitable material and is connected through a lead 68 to said conductor 62. Positioned within said cylindrical electrode 60 is the resistance heater 82 of tungsten, molybdenum or the like which is connected through the leads 84 and 85 to a coil 86 which is in position to be energized through said primary 58.

In Fig. 4 is shown a sealed envelope 90 having mounted therein, one at each end, the hollow cylinders 92 and 94 of metal such as iron, nickel or tungsten each of which has on either or both of its surfaces a coating of an oxide, hydroxide or carbonate of a metal such as barium, strontium or calcium. Within said cylinders 92 and 94 respectively, are mounted the heating resistors 96 and 98 respectively, resistor 96 being connected through the conductors 100 and 102 to the ends of a coil 104 mounted in operative relation to a transformer primary 106. In like manner the resistance 98 is connected through conductors 108 and 110 to the coil 112 which is also in operative relation to said primary 106. Connection is made from the cathode 92 through the conductor 114, ballast resistance 116, to one end of a transformer secondary 118 the other end of which secondary is connected through conductor 120 and resistance 116, to the cathode 94. Connection is also made from cathode 92 to lead 100 and from cathode 94 to lead 110, if desired.

In Fig. 5 is illustrated a closed envelope 130 which has mounted at one end thereof the two anodes 132 and 133 which connect through the resistances 136 and 138 respec-

tively to opposite ends of the transformer secondary 140 which is in operative relation to the transformer primary 142. At the end of said envelope 130 opposite said anodes is mounted the hollow cylinder 144 which is of metal such as iron, nickel or tungsten and which has over either or both of its surfaces a coating of an oxide, hydroxide or carbonate of barium or calcium or the like. Said electrode 144 connects through the conductor 146 to the inductance 148, thence by conductor 150 to an intermediate point on said transformer secondary 140. From a point between said resistance 136 and the secondary 140 connection is made through the resistance 155, and in some cases bimetallic element 157 and contact 161 of the thermostat device 159, conductor 152, resistance 153, and the mercury switch 154 to a point on said conductor 146. Said mercury switch 154 is normally in the closed position and has mounted thereto an armature 156 in operative relation to said inductance 148 for the moving of said switch 154 into the open circuit position by said inductance 148 when the latter is energized. About said electrode 144 is positioned the sleeve 160 of metal such as nickel, iron or tungsten which is connected through the lead 162 to said conductor 146. A heating resistor 164 mounted within said cylinder 144 is connected to the transformer secondary 166 through the leads 168 and 170.

In the envelope of the devices illustrated in Figs. 1 to 5 there is provided an atmosphere of gas or vapor such as one of the rare gases, mercury, caesium or other suitable gas or vapor, or a mixture of some of these. A preferred embodiment of the invention is any one of the discharge devices illustrated in the drawing and herein described with an atmosphere comprising about 90% helium and 10% neon.

In the use and operation of the device and apparatus of Fig. 1 a direct current potential is applied from the leads 5 to 20 across the anode 3 and cathode 12 through the inductance 18 and resistance 16 which serve to stabilize and regulate the current flow. Said cathode 12 is brought to an electron emitting condition by heat supplied from said resistor 6 which is connected on one side to said main 20 at a point between lead 14 and resistance 16 and on the other through the switch 22 and resistance 24 to said main 5. Preferably said resistance 6 is maintained energized during operation of the device to keep said cathode element 12 heated and in an electron emitting condition but switch 22 may be opened after the starting of discharge operation in certain cases where current passage through element 12 keeps that element in a sufficiently heated condition to maintain electron emission therefrom. It is to be understood that said resistor 6 can be heated by 130

means of a current from another source such as a storage battery in place of from said mains 5 and 20.

In a preferred form of device such as is illustrated in Fig. 1 the electron emissive coating 13 on said electrode 12 is the oxide of either barium, strontium or calcium. The oxide is applied as such in the form of a paint with water, zapon, cellulose or varnish as the vehicle, or the oxide coating is obtained by applying a coating of the hydroxide or carbonate which is decomposed by heat to leave the oxide on the electrode.

In the use of the device said resistor 6 is utilized to heat the electrode 12 and the oxide coating 13 on electrode 12 to bring it to an electron emitting state. These electrons will be emitted into the space in the device in which there is a potential gradient and will be impelled toward said anode 3 and be discharged thereat, thereby effecting current flow in the device. Further, in their movement across the space the electrons will be accelerated and they will collide with gas or vapor atoms or molecules and thereby transfer to these atoms or molecules energy which causes them to emit radiations in the visible and in the invisible ranges.

The operation of the device and system of Fig. 2 is similar to that of Fig. 1 as regards the function of the cathode. The device of this figure is for use on alternating current and is adapted for rectifying alternating current according to the functioning and manner of operation of the Cooper Hewitt rectifying lamp well known in the arts. The resistor 42 is energized from an intermediate section of the transformer secondary 38 which is connected thereto by said leads 44 and 45. The electrode 46 is connected to an intermediate point on said secondary 38 through lead 48 and one of said leads 44 and 45.

The device of Fig. 3 functions somewhat similarly to that of Fig. 2 except that a separate energizing coil 86 positioned in operative relation to the primary 58 is connected across the resistor 82 to supply heating current thereto. Connection is made from an intermediate point on the secondary 56 through the inductance 64 to said electrode 60 and to the cylindrical shield 66, the ends of said secondary 56 being connected through resistances 54 and 55 respectively to anodes 132 and 133.

The device of Fig. 4 is for use on alternating current and for conducting the current in both directions between said distant electrodes 92, 94. During alternate half cycles of current flow resistors 96 and 98 serve to maintain the electrodes 92 and 94 in cathode condition by continuous energization of the oxide coatings thereon to keep them in the electron emitting state. During operation current will flow alternately from opposite

ends of said main secondary 118 to alternate ones of said electrodes 92 and 94 and thence through the discharge space in envelope 90 to the other of the electrodes and then back to said secondary 118, and the resistances 116 serve to regulate current flow therein. As in the case of the device of Fig. 1, in some cases discharge producing current flowing through said electrodes 92 and 94 will be sufficient to heat the metal oxide coatings thereon and maintain them in the electron emissive condition through the zero point of alternations of current flowing therethrough, the heaters then being unnecessary after a discharge has been initiated.

The device of Fig. 5 is similar to that of Fig. 3 but includes means comprising inductance 148 and switch 154 for producing a high voltage surge across the lamp to start it into operation, in cases where desired. In the operation of the starting means, before current commences to flow between the electrodes of the discharge device and when said primary 142 is properly energized, current will flow from the mid-point of said secondary 140 through the lead 150, inductance 148, switch 154, resistance 153, lead 152, resistance 155, which is the heater element of thermostat 159, back to the secondary. The current flowing through the circuit just described is insufficient to open the mercury switch 154 and the heating of the resistance 155 continues for a predetermined time, that is, the time it will take the heater resistance 164 to bring the oxide coated cathode 144 to a temperature at which it will operate efficiently as a cathode. During this interval the bimetallic member 157 of the thermostat 159 is affected by the heat from the resistance 155 and in forty-five seconds, say, the bimetallic bar will deform and come into contact with the terminal 161, shortcircuiting the resistance 155 and thereby increasing the current through the circuit to energize the inductance 148 to a value sufficient to attract the armature 156 on the mercury switch 154, thus producing a sudden break in the current flowing through said part of said secondary 140 whereby there is produced a static discharge from said anode 132 and said cathode including the cylinders 144 and 160. In the meantime said resistor 164 has been energized from said secondary 166 and the oxide coating on said cylinder 144 brought to the electron emissive state. Such a high potential discharge between the cathode and the anode will start current flow from the anode to the cathode because potential difference has been maintained from the beginning between said electrodes. Upon commencement of regular discharge current flow through said cathode said inductance 148 will be maintained in the energized condition and will hold said switch 154 in the open circuit position.

While I have described the invention in

connection with an oxide coating on the cylinders 12, 46, 60, 66, 92, 94, 144 and 160, it is understood that in place thereof cylinders of electron emissive metals such as barium, strontium, thorium or beryllium, or alloys rich in such electron emissive metals, may be substituted.

When oxide coated electrodes are used the life of such cylinders is extended when desired by introducing into the lamp a small quantity of a material having a reducing effect on the oxides, such as potassium, magnesium or carbon, whereby there is maintained a continuous supply of electron emitting material on the cathode, as well as the desired purity of the gas when neon alone is used, or of the components of a mixture such as neon and helium when that mixture is used.

It is to be understood that while I have described the invention as applied to a neon-helium lamp the elements in combination are applicable to lamps in which one gas alone is used as the radiation and current carrying material.

In the claims the term "gas" has been freely used, and is intended to cover vapor as well as gas.

I claim as my invention:

1. A gaseous discharge device comprising an envelope, electrodes therein, one of which is adapted to emit electrons when heated, means for heating said electrode, and a mixture of helium and neon therein, the helium constituting at least 85% of said mixture.

2. A gaseous discharge device comprising an envelope, electrodes therein, one of which is adapted to emit electrons when heated, means for heating said electrode, and a mixture of helium and neon therein, the helium comprising substantially 90% of said mixture.

3. A gaseous discharge device comprising an envelope, electrodes therein, one of which is adapted to emit electrons when heated, means for heating said electrode, and a mixture of gases within said envelope in combination with means for initiating a discharge through said device and means for delaying the operation of said means for initiating a discharge until said electrode has reached an operating temperature.

4. A gaseous discharge device comprising an envelope, electrodes therein, one of which is adapted to emit electrons when heated, means for heating said electrode, and a mixture of rare gases within said envelope, in combination with means for initiating a discharge through said device, and means for delaying the operation of said means for initiating a discharge until said electrode has reached an operating temperature.

5. A gaseous discharge device comprising an envelope, electrodes therein, one of which is adapted to emit electrons when heated,

means for heating said electrode, and a mixture of gases therein, said mixture having a low average atomic weight, in combination with means for initiating a discharge through said device and means for delaying the operation of said means for initiating a discharge until said electrode has reached an operating temperature.

6. A gaseous discharge device comprising an envelope, electrodes therein, one of which emits electrons when heated, means for heating said electrode, means within said envelope reacting with said electron emitter to maintain it in electron emitting condition, and a mixture of gases within said envelope in combination with means for initiating a discharge through said device and means for delaying the operation of said means for initiating a discharge until said electrode has reached an operating temperature.

7. A gaseous discharge device comprising an envelope, electrodes therein, one of which emits electrons when heated, means for heating said electrode, a mixture of gases within said envelope, and means in said envelope for maintaining the purity of said gas mixture in combination with means for initiating a discharge through said device and means for delaying the operation of said means for initiating a discharge until said electrode has reached an operating temperature.

8. An electric gaseous discharge device comprising an envelope, electrodes within said envelope, one of said electrodes being capable of emitting electrons when heated, means for heating said electrode, a gas of low atomic weight and given ionizing potential in said envelope, and another gas having a higher atomic weight and a lower ionizing potential than said first mentioned gas intermixed therewith, the proportion of said gas of higher atomic weight being the minimum which will cause the characteristic radiations of said gas to predominate upon passage of an electrical discharge between said electrodes.

Signed at Hoboken in the county of Hudson and State of New Jersey this 24th day of October, A. D. 1928.
